(57) **CLAIM**

The ornamental design for a gift box, as shown and described.

DESCRIPTION

FIG. 1 is a front perspective view of a top of a gift box
according to the present design;

FIG. 2 is a top plan view of a top of a gift box as shown in FIG.
1;

FIG. 3 is a bottom plan view of a top of a gift box as shown in
FIG. 1;

FIG. 4 is a front view of a top of a gift box as shown in FIG.
1;

FIG. 5 is a right side view of a top of a gift box as shown in
FIG. 1;

FIG. 6 is a rear view of a top of a gift box as shown in FIG. 1;
FIG. 7 is a left side view of a top of a gift box as shown in FIG.
1;

FIG. 8 is a front perspective view of a bottom of a gift box as
shown in FIG. 1;

FIG. 9 is a top plan view of a bottom of a gift box as shown in
FIG. 8;

FIG. 10 is a bottom plan view of a bottom of a gift box as
shown in FIG. 8;

FIG. 11 is a front view of a bottom of a gift box as shown in
FIG. 8;

FIG. 12 is a side view of a bottom of a gift box as shown in
FIG. 8;

FIG. 13 is a rear view of a bottom of a gift box as shown in
FIG. 8;

FIG. 14 is a left side view of a bottom of a gift box as shown
in FIG. 8;

FIG. 15 is a front perspective view of a gift box with the top
of a gift box as seen in FIG. 1 and the bottom of a gift box as
seen in FIG. 8;

FIG. 16 is a top plan view of the gift box as shown in FIG. 15;
FIG. 17 is a bottom plan view of the gift box as shown in FIG.
15;

FIG. 18 is a front view of the gift box as shown in FIG. 15;

FIG. 19 is a right side view of the gift box as shown in FIG. 15;
FIG. 20 is a rearview of the gift box as shown in FIG. 15;

FIG. 21 is a left view of the gift box as shown in FIG. 15; and,
FIG. 22 is a exploded view of the gift box as shown in FIG. 15.
